Primary Examiner — W. A. Teddy Falloway*Assistant Examiner* — Amanda Kay Birdwell(74) *Attorney, Agent, or Firm* — Mitchell Law PLLC;
Matthew W. Mitchell(57) **CLAIM**

The ornamental design for a resealable silicon bag, as shown and described.

DESCRIPTION

FIG. 1 is a front perspective view showing my new design;
FIG. 2 is rear perspective view thereof;
FIG. 3 is another rear perspective view thereof;
FIG. 4 is yet another rear perspective view thereof;
FIG. 5 is a rear view thereof;
FIG. 6 is a front view thereof;
FIG. 7 is a right-side view thereof;
FIG. 8 is a left-side view thereof;
FIG. 9 is a top plan view thereof; and,
FIG. 10 is a bottom view thereof.

The broken lines show the interior portions that form no part of the claimed design.
